UNITED STATES PATENT OFFICE.

EDWARD P. SHELDON, OF NEW YORK, N. Y., ASSIGNOR TO R. HOE AND CO., OF NEW YORK, N. Y., A CORPORATION OF NEW YORK.

ASSOCIATING MECHANISM.

Application filed November 28, 1922. Serial No. 603,808.

To all whom it may concern:

Be it known that I, EDWARD P. SHELDON, a citizen of the United States, residing at New York city, county of Kings, and State 5 of New York, have invented certain new and useful Improvements in Associating Mechanism, fully described and represented in the following specification and the accompanying drawings, forming a part of 10 the same.

This invention relates to certain improvements in associating and delivering mechanism for web printing machines.

In certain types of associating and delivering mechanisms for web printing machines a sheet, cut from a web or from any suitable source of sheet supply, is associated with one or more sheets cut from a web from another source, cutting and collecting cylinders being employed for associating the sheet with the web and cutting a sheet or sheets from the web for association. The associated cut sheets then go to the former or other folding apparatus, such a type of 20 machine being illustrated in my prior Patent No. 572,225, dated December 1, 1896. In this type of machine the associated product is delivered to the former from the last pair of cutting and collecting cylinders by means 30 of rolls, which take the product and forward it to the former. Where these rolls are employed it frequently happened that the product slipped a little and did not advance the tail of the cut sheet past the cutting line when the sheet was cut from the web with which the cut sheet had been associated, the cut sheet having a tendency to slip back somewhat so that the tail of this sheet was again cut when the sheet was severed from the web, this resulting in so-called double cutting of the sheet, which is 40 objectionable.

It is the especial object of the present invention to improve the mechanism of this type of machine, to prevent this double cutting, the cut sheet or sheets and the web being positively seized and advanced beyond the last cutting mechanism, so that the cut sheet or sheets cannot slip back when a sheet associated therewith is to be cut from a web, the tail of the cut sheets being advanced slightly past the cutting line so that double cutting is prevented.

With this and other objects not specifically referred to, the invention consists in

certain novel parts, arrangements and combinations, which will be specifically described in connection with the accompanying drawing and the novel features then pointed out in the claims hereunto annexed. 60

In this drawing—

The figure is a side elevation, partly in section and partly broken away, of so much of the delivery end of a web printing machine as is necessary for an understanding 65 of the invention.

Referring now to this drawing, in the particular embodiment of the invention illustrated, a web is forwarded at full speed and a second web is forwarded at a slower speed than the full speed web. Sheets are cut from this slow speed web and associated with the high speed web the sheets then being cut therefrom, and furthermore in the particular embodiment of the invention 75 illustrated, the slow speed web will be associated between two sheets from the full speed web though it will be understood that the invention may be used in associating and delivering products other than specifically shown. 80

The low speed web, which in the present instance, is a web running at half speed, is indicated by the letter H. This web after being printed in a suitable printing mechanism, not illustrated, passes over a guide roll 1 suitably supported in brackets 2 secured to the main side frames 3 of the machine. From the guide roll the web passes between a pair of driving and forwarding rolls 4, 5 to a pair of cutting and forwarding cylinders marked 6, 7, mounted on shafts 6', 7', suitably mounted on standards 600 supported from the frames of the machine, the cylinder 7 being provided with a cutting 90 knife 8 and the cylinder 6 being provided with oppositely disposed cutting woods 9. 95

In the particular construction illustrated the cylinder 6 is twice the size of the cylinder 7 and is driven at half speed. This cylinder is provided with sheet taking devices in the form of pins 10 which are operated in the usual manner to impale a sheet and forward it. 100

A full speed web marked F after being printed in any suitable printing mechanism, not shown, is forwarded over a guide roll 11, suitably journaled in the side frames 3 of the machine to a pair of driven forwarding rolls 12, 13, suitably mounted in the side 110

frames and from these rolls is led to a pair of cutting and collecting cylinders 14, 15, the cylinder 15 being provided with a cutting knife 16 and cylinder 14 being provided 5 with a cooperating cutting wood 17. These cylinders 14 and 15 are provided with sheet taking devices, as pins 18, operated in the usual manner and these two cylinders are driven at high speed, that is, the speed of 10 the full speed web F, and are one half the size of the cylinder 6. These cylinders 14, 15 are mounted on shafts 14', 15' supported in standards 150 on the machine frame.

The sheets cut from the half speed web 15 are forwarded so as to be taken by the sheet taking pins on the cylinder 14 and brought up to full speed. While this may be effected in various ways, in the particular construction illustrated, the cylinder 6 is 20 provided with cut-away or depressed portions 19 in advance of which are feeding segments 20 which cooperate with a roll 21 to feed the sheet forward, after they are released by the sheet taking pins 10. As the 25 depressed portion 19 passes the roll 21 the sheet is released and as at this time the pins 18 on cylinder 14 have taken the head end of the sheets the tails of the sheets are free so that they can be taken at the high speed 30 of the cylinder 14. The cut sheets from the half speed web H are forwarded to the cylinder 14 between suitable guides 22, 23 and are fed up to these guides by the feeding segments 20 and the feed roll 21.

35 In the particular construction illustrated a half speed sheet is forwarded to the cylinder 14, after a full speed sheet has been taken thereby, and this half speed sheet and full speed sheet are associated with the full 40 speed web, so that the half speed sheet will be between two full speed sheets, the second full speed sheet being severed from the web after association. In accordance with the invention means are provided whereby 45 double cutting of the associated sheets is prevented as the web is severed to cut off the second high speed sheet. While this means may be somewhat varied, they will include devices for positively seizing the 50 sheets and the associated web, and forwarding them so that no slip can occur that will bring the tail of the sheets into the cutting line, the forwarding devices being so arranged that the tail of the sheets is advanced slightly beyond the cutting line at the time of the cut.

55 In the particular construction illustrated these devices for positively seizing and forwarding the associated product are pins 24, 60 which are mounted on a forwarding carrier shown as a cylinder 25. Where the carrier is a cylinder this cylinder will be arranged so as to be slightly out of axial alignment with the cutting and collecting cylinders 14, 15, so that the tail of the sheets are for-

warded slightly beyond the cutting line of cylinders 14, 15 at the time they act to sever the sheets from the web. As shown, the shaft 26 of cylinder 25 is arranged slightly above the shafts 14', 15' of cylinders 14, 15. 70 Cooperating with the cylinder 25, is a forwarding roll 27 which acts to forward the products to the former 28, or to any other desired mechanism.

75 It will be observed that when the cut sheet is associated with the web on the cylinder 15 it occupies a position on the outside of the cylinder, the web being on the inside, this position being maintained until the web and the sheet pass to the cylinder 25, at 80 which time, however, they have been seized by the sheet taking pins 24. The cut sheet is therefore spaced from the cylinder the thickness of the web. While this spacing is very slight, it is sufficient to thus slightly 85 advance the sheet so that the tail of the sheet is just beyond the cutting line at the time of the cut. This slight advance is maintained by positioning the forwarding cylinder 25 slightly out of axial alignment 90 with the cutting cylinder 15. This positioning of the cylinders causes a tight hug of the web and the associated sheet around the surface of the cylinder and prevents any tendency of the sheet to slip back so that 95 the tail falls into the cutting line at the time of the cut. It will be observed, furthermore, that the sheets are under a positive direct engagement from the time they are taken by the pins 18 on the cylinder 14 100 until they pass into the bite of the forwarding roll 27, so that there is no liability of the sheet slipping, that is, during and after association the sheets are positively controlled and are not simply pushed forward. Furthermore, the structure is compact and 105 can be conveniently arranged at the folder end of the machine.

110 If desired for the production of certain products, the web H may be led directly to the cutting and collecting cylinders 14, 15, over a guide roll 29, and associated with the web F, or both webs H and F may be associated at the cylinder 25, and led to the former.

115 While the invention has been shown and described in its preferred form, it will be understood that certain variations and changes may be made in the specific constructions shown and described and that the invention is not to be limited to the exact mechanism illustrated.

120 What is claimed is:

1. The combination with means for associating a cut sheet and a web, means for 125 cutting a sheet from the web after association, and means located beyond the associating and cutting mechanism for positively seizing and advancing the associated web and sheet so that the tail of the sheet is 130

prevented from slipping back into the cutting line when the sheet is severed from the web.

2. The combination with means for associating a cut sheet and a web, means for cutting a sheet from the web after association, and a forwarding cylinder located beyond the associating and cutting mechanism provided with sheet taking devices for seizing the associated web and sheet so that the tail of the sheet is prevented from slipping back into the cutting line when the sheet is severed from the web.

3. The combination with collecting and cutting cylinders for associating a sheet and a web and cutting a sheet therefrom after association, of forwarding devices acting to positively forward the sheet and web so that the tail of the sheet is advanced slightly beyond the cutting line at the time the sheet is cut from the web.

4. The combination with collecting and cutting cylinders for associating a sheet and a web and cutting a sheet therefrom after association, of a forwarding cylinder having sheet taking devices for positively forwarding the sheet and web, said forwarding cylinder being mounted out of axial alignment with the cutting and collecting cylinders, whereby the tail of the sheet is advanced slightly beyond the cutting line at the time the sheet is cut from the web.

5. The combination with means for advancing a web at half speed, means for cutting sheets therefrom, means for advancing a web at full speed and cutting sheets therefrom, means for associating a half speed sheet with a full speed web, and means for positively seizing and advancing the sheet and web so that the tail of the sheet is slightly beyond the cutting line at the time the sheet is cut from the full speed web.

6. The combination with means for advancing a web at half speed, means for cutting sheets therefrom, means for advancing a web at full speed and cutting sheets therefrom, means for associating a half speed sheet with the full speed web, and a cylinder provided with sheet taking devices for positively seizing the sheet and web, and arranged to advance the tail of the sheet slightly beyond the cutting line at the time the sheet is cut from the full speed web.

7. The combination with means for advancing a web at half speed, means for cutting sheets therefrom, means for advancing a web at full speed and cutting sheets therefrom, means for positioning a half speed sheet between a full speed sheet and the full speed web, and means for positively seizing and advancing the sheets and web so that the tail of the sheet is slightly beyond the cutting line at the time the sheet is cut from the full speed web.

8. The combination with means for ad-

vancing a web at half speed, means for cutting sheets therefrom, means for advancing a web at full speed and cutting sheets therefrom, means for positioning a half speed sheet between a full speed sheet and the full speed web, and a cylinder provided with sheet taking devices for positively seizing the sheets and web, and arranged to advance the tail of the sheet slightly beyond the cutting line at the time the sheet is cut from the full speed web.

9. The combination with means for advancing a web at half speed, means for cutting sheets therefrom, cutting and collecting cylinders for advancing a web at full speed and cutting sheets therefrom, means for positioning a half speed sheet between a full speed sheet and the full speed web, and a cylinder provided with sheet taking devices for positively seizing and forwarding the sheets and web, said cylinder being mounted out of axial alignment with the cutting and collecting cylinders, whereby the tail of the sheet is advanced beyond the cutting line at the time the sheet is cut from the web.

10. The combination with cutting and collecting cylinders running at high speed, of means for forwarding a web thereto, a cylinder running at a lower speed and provided with sheet taking devices for forwarding a sheet to the high speed cylinders for association with a web or sheet thereon, low places on the low speed cylinder to free the tail of a sheet after the head of the sheet has been taken by the high speed cylinders, and forwarding devices acting to positively seize the associated product and arranged to advance the product so that the tail of the sheet is beyond the cutting line when a sheet is cut from the high speed web.

11. The combination with cutting and collecting cylinders running at high speed, of means for forwarding a web thereto, a cylinder running at a lower speed and provided with sheet taking devices for forwarding a sheet to the high speed cylinders, means for freeing the tail of the sheet while on the low speed cylinder after the head of the sheet has been taken by the high speed cylinders, and forwarding devices acting to positively seize the associated product and arranged to advance the product so that the tail of the sheet is beyond the cutting line when a sheet is cut from the high speed web.

12. The combination with cutting and collecting cylinders running at high speed, of means for forwarding a web thereto, a cylinder running at a lower speed and provided with sheet taking devices for forwarding a sheet to the high speed cylinders, means for freeing the tail of the sheet while on the low speed cylinder after the head of the sheet has been taken by the high speed

cylinders, and a forwarding cylinder provided with sheet taking devices to advance the product so that the tail of the sheet is beyond the cutting line when a sheet is cut 5 from the high speed web.

13. The combination with means for associating a cut sheet and a web, means for cutting a sheet from the web after association, folding mechanism, and means interposed between the folding mechanism and the sheet cutting means for positively seizing and advancing the associated web and sheet so that the tail of the sheet is advanced slightly beyond the cutting line at 10 the time the sheet is cut from the web.

14. The combination with means for associating a cut sheet and a web, means for cutting a sheet from the web after association, folding mechanism, and a cylinder interposed between said folding mechanism 20 and the sheet cutting means, said cylinder being provided with sheet taking devices for positively seizing and advancing the associated web and sheet so that the tail of the sheet is advanced slightly beyond the 25

cutting line at the time the sheet is cut from the web.

15. The combination with means for associating a cut sheet and a web from different sources, means for cutting a sheet from the web after association, and means for positively seizing and advancing the associated web and sheet so that the tail of the sheet is prevented from slipping back into the cutting line when the sheet is severed from the web. 30

16. The combination with means for associating a cut sheet and a web from different sources, means for cutting a sheet from the web after association, and means located 40 beyond the associating and cutting mechanism for positively seizing and advancing the associated web and sheet so that the tail of the sheet is prevented from slipping back into the cutting line when the sheet is 45 severed from the web.

In testimony whereof, I have hereunto set my hand.

EDWARD P. SHELDON.
